UNITED STATES PATENT OFFICE.

JOHN SHERMAN McCHESNEY, OF CHICAGO, ILLINOIS, ASSIGNOR, BY MESNE ASSIGNMENTS, TO CARY MANUFACTURING CO., OF BROOKLYN, NEW YORK, A CORPORATION OF NEW YORK.

WIRE-SPlicing TOOL.

Application filed March 31, 1919, Serial No. 286,242. Renewed August 14, 1922. Serial No. 581,843.

To all whom it may concern:

Be it known that I, JOHN SHERMAN McCHESNEY, citizen of the United States, residing at Chicago, Illinois, have invented 5 certain new and useful Improvements in a Wire-Splicing Tool; and I do hereby declare the following to be a full, clear, and exact description of the invention, such as will enable others skilled in the art to which it applies 10 to make and use the same.

My invention relates to the joining of wire portions by means of twists, one of its general objects being to provide a simple, effective and easily manipulated appliance for 15 producing a firm, uniform and substantially straight twist and to do this without holding the wires under tension. In my copending application, filed March 31, 1919 as Serial No. 286,241 I have shown a tool for this 20 purpose, operated through a gear carried by a shaft and arranged for clamping overlapped wire portions to hold these against rotation during the making of the twist. In that case, the twist was made by relatively 25 rotating the overlapping wire portions disposed at opposite ends of the proposed twist while firmly gripping one pair of these portions and slidably holding the other pair against relative rotation.

In my present invention I aim to provide 30 an appliance construction in which both of the relatively rotated pairs of overlapped wire portions are confined against relative rotation of the wires comprising each portion, but are both free to move longitudinally with respect to the confining means. I 35 also aim to provide a simplified operating mechanism which will eliminate the gearing, and in which one of the wire-confining means 40 will automatically be moved into and out of its operative position during the manipulation of the appliance. Furthermore, I aim to provide simple means for affording a suitable handhold during the operation of the 45 appliance, and simple means for assembling the same out of relatively few parts. Still further objects will appear from the following specification and from the accompanying drawings, in which.

Fig. 1 is a perspective view of an appliance embodying my invention.

Fig. 2 is an enlarged plan view of the head of the same and of a portion of the actuating shank.

Fig. 3 is a central and longitudinal section 55 taken vertically of the tool along the center line of Fig. 2.

Fig. 4 is a section taken centrally of the operating shank along the correspondingly numbered line in Fig. 3, and showing the 60 finished twist while being withdrawn from the tool.

Fig. 5 is a longitudinal section through the forward end of the shank and through the twist-confining tube carried thereby, taken 65 at right angles to the section of Fig. 4.

Fig. 6 is a transverse section taken along the correspondingly numbered line of Fig. 3.

Fig. 7 is a transverse section through the shank of the appliance, taken along the correspondingly numbered line in Fig. 5.

Fig. 8 is a fragmentary section similar to Fig. 4, but showing the tool just before the intertwisting of the wires is begun.

In my present invention, I also employ the 75 novel principle of operation underlying the appliance of my said copending application, namely the fact that a straight and uniform twist may be made in a pair of overlapping wires without having these wires under tension during the twist, provided that the portions of the wires which are to be intertwined are so confined as to prevent a kinking or "hunting" of the wires during the making of the twist. For this purpose, I 80 employ a confining tube 1 desirably made of hardened steel, and having the main portion of its bore of more than twice the diameter of each of the two wires which are to be intertwined. This bore is flattened at its rear 85 end for a length of more than twice the diameter of one of the wires, or into a flattened bore which will slidably house two overlapped wire portions without permitting these wire portions to twist about each 90 other within the said flattened bore portion. The confining tube 1 is mounted in the forward end of a shank 2, which shank is rotatably mounted in a head 3 and is adapted to be rotated by suitable means, such as a 95 crank shaft 4. The shank 2 is slotted from one side back of the tube 1, as shown in Figs.

5 and 7, thus affording a passage for inserting one of the wires into the rear end of the confining tube 1.

The head 3 has a mouth at its forward end 5 and has mounted in the said mouth suitable means for confining the overlapped wire portions forwardly of the confining tube 1, as for example pivoted clamping levers 5. In the embodiment illustrated, these levers 10 are pivoted on pins 6 slipped into bores extending part way upward through the head 3 of the appliance, the pins being held from dropping out by a shoe 7 to which the head is riveted.

15 To move these levers 5 into their wire-confining position, I desirably provide these with cam formations 14 adapted to engage the forward end of the shank 2, and mount this shank so that it can slide 20 in the head 3 for engaging with the cam levers and forcing the latter into their wire-confining positions. To permit of this sliding, I may mount a pin 8 transversely in the head 3, which pin engages a contracted 25 part of the shank 2, so as to limit the movement of this shank with respect to the head. Then I desirably equip the rear end of the head 3 with lugs 9 affording handles which may be grasped by the operator for holding 30 the head of the appliance firmly in position while sliding the shank 2 with respect to the head and while rotating the crank shaft 4. The jaws of the levers 5 are desirably slightly greater in width than 35 the combined thickness of the two wires with which the appliance is to be used and desirably so arranged so as to approach each other by a distance slightly greater than the thickness of a single wire when 40 the jaws are swung inward into the position shown in Fig. 4 by the cam action of the end of the shank 2.

In using my appliance for splicing an extension wire 10 to a wire 11, the latter is 45 inserted through the mouth of the appliance and the entire length of the confining tube 1 while the operating handle is in the position of Figs. 1 and 5, or in a position in which the flattened bore portion extends 50 vertically as in Figs. 6 and 7. Then the extension wire 10 is introduced from the rear of the head through the slot in the shank 2 and above the wire 11, with the forward end of this wire 10 extending 55 slightly beyond the jaws of the levers 5. This is desirably done after the levers 5 have been swung to their confining positions as shown in dotted lines in Fig. 4, so that the jaws of these levers will hold the 60 wire one above the other. Thus arranged, it will be obvious that the two wires are slidably confined at opposite ends of the main bore of the tube 1, and that the portions of the wires confined by the flattened 65 bore portion of the tube 1 can readily be

rotated with respect to those confined by the jaws, by merely rotating the crank shaft 4. During such rotation, the bore of the tube 1 will prevent the twist formed within this bore from bowing or kinking, 70 thus insuring a straight and uniform twist which can readily be judged as to its extent by simply counting the number of rotations given to the crank-shaft 4. In practice, I desirably give this crank-shaft an 75 odd number of half-turns, so as to end with the rear portion of the wire 10 directed downwardly, or in the same direction from the twist as the forward part of the wire 11. By doing this and instructing the 80 operator to give the crank of the appliance a definite number of half-turns, I can readily predetermine both the extent of the twist and the direction of the free tips of the twist, even when employing inexperienced 85 help, thus also insuring a twist of ample strength without overstraining the wire.

When the twist is finished, a backward pull on the shank 4 will slide this back to the position of Fig. 4, thus leaving the rear 90 portions of the levers 5 free to swing inwardly. Then on pulling the tool back further with respect to the wires, the twist will engage the confining jaws as shown in Fig. 4, so as to move these to their open position, thus permitting the twist and the rear portion of the wire 10 to be drawn entirely out of the appliance. To prevent the levers 5 from swinging too far when thus moved, I desirably equip them at their rear 100 ends with extensions 15 adapted to engage the side of the head, thereby leaving the cam portions of these levers in suitable positions for engagement by the forward end of the shank 2.

105 With a tool thus arranged, it will be obvious that the movement of the levers 5 is practically automatic, so that the operator merely needs to insert the two wires, rotate the crank to the desired extent and pull the 110 appliance off the intertwined wires, whereupon a forward sliding of the shank restores the jaws to their initial confining position. Moreover, since the wires are not gripped at either end, but only slidably confined, the 115 same appliance may be used with wires of considerably varying diameters and the tool will still function after the parts have had considerable wear during extensive use. Where my tool is to be used for splicing 120 extensions to the wires on wire-bound boxes, I desirably provide the shoe 7 with prongs 12 for use in raising the terminal portions of stapled wires, after the manner more fully described in my said copending application, and also dispose the shoe in a plane at an angle to the axis of the shank 2. However, while I have illustrated and described my appliance in a highly desirable 125 embodiment, I do not wish to be limited 130

to the details of construction and arrangement here disclosed, it being obvious that the same might be modified in many ways without departing from the spirit of my

invention.

I claim as my invention:

1. For intertwisting two longitudinally parallel wire portions, two relatively rotatable means spaced along the said wire portions, both of the said means slidably housing the wires between walls spaced by less than the sum of the diameters of the wires, and twist-straightening means disposed between the aforesaid means and having a bore approximating the said sum of the diameters.

2. In an appliance for intertwisting two wires, a rotatable tubular member whose bore includes an end portion formed for freely housing the intertwined portion of the proposed splice, a flattened intermediate portion formed for slidably housing two parallel wire portions while preventing relative rotation thereof, and another end portion opening laterally of the said member to permit the insertion of wire into the said bore.

3. In a tool for intertwisting longitudinally overlapped portions of two wires, a rotatable member having an axial bore terminating at one end of the said member and opening into a lateral passage spaced from the said end, the said bore being contracted intermediate of its ends to a width less than twice the diameter of either of the said wires.

4. In an appliance for intertwisting longitudinally overlapped portions of two wires, a rotating member having a bore adapted to house overlapped portions of the wires, a support in which the said rotating member is both rotatably and slidably mounted, and wire-confining means in alignment with the axis of the said member and responsive in operation to the sliding of the member in one direction.

5. In a wire twisting appliance, a support, a twisting member slidably and rotatably carried thereby, and a pair of jaw levers pivoted upon the support symmetrically with respect to the axis of the rotating member, the said levers and the rotating member having cooperating formations for causing a sliding of the rotating member in one direction to approach the jaws of the levers to each other.

6. In a wire twisting appliance, a support, a twisting member slidably and rotatably carried thereby, and a pair of jaw levers pivoted upon the support symmetrically with respect to the axis of the rotating member, the said jaw levers and the rotating member having cooperating formations for causing a sliding of the rotating member in one direction to approach the jaws of the levers to each other, the rotating member having a

bore housing the twist during the making thereof, and the levers having formations engaged by the twist upon a pulling of the latter out of the said bore for swinging the jaws away from each other.

70

7. An appliance as per claim 6, in which the jaw-levers have stop portions engaging the support to limit the said separational movement of the jaws.

8. In an appliance for intertwisting portions of two wires, a twisting member, a support upon which the said member is rotatable, the support having a pair of parallel bores disposed symmetrically with respect to the axis of the twisting members, pivot pins slidably disposed in the said bores, wire-confining levers pivoted respectively on the said pivot members, and a shoe secured to the support and retaining the pivot pins in the said bores.

85

9. In an appliance for intertwisting two wires, a twisting member, and a support upon which the said member is mounted with freedom for independent rotational and longitudinal movement, the twisting member and the support each having handle formations adapted to be grasped by the respective hands of the operator.

90

10. In an appliance for intertwisting two wires, a twisting member including a shank having a tubular part equipped with contracted neck portion and having a lateral recess connected to the bore of the tubular portion, a support having a bore entered by the said shank; and means within the bore of the support adapted to engage a shoulder of the said neck portion to limit the sliding of the twisting member longitudinally of the bore in the support.

100

11. In an appliance for intertwisting portions of two wires, a support equipped for non-rotatably confining portions of the overlapped wires, and a twisting member rotatably mounted upon the support and including a shank having a bore extending from one end thereof axially of the shank and open laterally of the latter intermediate the ends of the shank, the shank having a crank formation adjacent to its other end.

110

12. In an appliance for intertwisting two wires, a twisting member including a shank having an axial bore extending thereinto from one end thereof and having a slot extending from a side of the shank and meeting the said bore, and a tube mounted in the said bore and having the bore of the tube flattened at a distance from the end of the shank and in alignment with the said passage.

120

13. In a wire twisting appliance, a support, gripping means carried by the support for retaining a plurality of wires in substantially fixed and lapping relation to each other, and a tubular member mounted

130

in said support independently of said gripping means, said tubular member being slid-
able and rotatable with respect to the gripping means, and said tubular member co-
operating with gripping means for opening and closing the latter upon the slidable
movement of said tubular member.

14. In a wire twisting appliance, gripping means including parts adapted for
10 opening and closing movement, and a slid-
able and rotatable twister co-operable dur-
ing said slidable movement with the said
gripping means for opening and closing the
latter.
15. 15. In a wire twisting appliance, a sup-
port, gripping means including parts adapt-

ed for opening and closing movement, and
a twister rotatable with respect to said grip-
ping means, said twister being movable to-
ward and from the gripping means and co-
operating therewith for opening and clos-
ing the parts by said to and fro movement.

16. In a wire twisting appliance, grip-
ping means including parts adapted for rel-
ative opening and closing movement, a slid-
ing member positioned for contact with
gripping means to open or close the parts
thereof upon the sliding movement of said
member, and a second member rotatable
with respect to the gripping means.

Signed at Chicago, March 26th, 1919.
JOHN SHERMAN McCHESNEY.
